CLAIM

The ornamental design for a baseball equipment bag, as shown and described.

DESCRIPTION

FIG. 1 is a perspective view of a baseball equipment bag showing my new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof;

FIG. 7 is a bottom plan view thereof;

FIG. 8 is a front elevational view, with the bag in open condition; the broken line showing of carrying straps in FIGS. 1, 2 and 6 and equipment in FIG. 8 being for illustrative purposes only and forming no part of the claimed design.
